CLAIM

The ornamental design for a roulette game, as shown and described.

DESCRIPTION

FIG. 1 is a perspective view of a roulette game in accordance with the present invention;

FIG. 2 is a top plan view thereof;

FIG. 3 is a perspective view of a section of the roulette game, shown broken away for ease of illustration; and,

FIG. 4 is a side perspective view of piece positioned adjacent to the section of the roulette game shown in FIG. 3.

The bottom of the roulette game shown in the figures is unornamented and forms no part of the claimed invention. The broken line showing of the wheel in FIGS. 1-2 is for illustrative purposes only, and forms no part of the claimed design.

1 Claim, 4 Drawing Sheets
